APPARATUS FOR PRODUCING A CONTINUOUS GLASS STRIP

Ernest Bristow Le Mare, St. Helens, England, assignor to Libbey-Owens-Ford Glass Company, Toledo, Ohio, a corporation of Ohio

Application December 12, 1938, Serial No. 245,117
In Great Britain February 8, 1938

2 Claims. (Cl. 49—33)

This invention relates to apparatus for producing a continuous glass strip, and has for its object a device for improving the flatness of the strip.

When a glass strip is formed continuously by rollers fed from a glass tank, the speed of formation is necessarily slow and the strip while plastic is liable to deformation if not supported at every point. In this respect difficulty has been found in supporting the strip in the interval between the forming roller and the next adjacent supporting means, whether this be a roller or a stationary bed. If it be a roller there is necessarily an interval between the line of contact of the strip with the forming roller and that with the supporting roller, and it is found that the edges of the strip sag downwards and are stretched in this interval. When the strip becomes flattened on its under surface by its subsequent supporting means, the stretched edge portions curl upwards and present difficulties in the grinding of the strip.

A triangular shaped bed has been used to bridge the interval between the forming roller and the next adjacent supporting means, but a bed in this position is subjected to so much heat, in the case of a continuous process in which there is no interval for cooling, that it has been found impossible to prevent its deformation, even when it is water-cooled. The same difficulty arises when the next adjacent supporting means is a stationary bed. If the stationary bed be continued up to the line at which the strip leaves the forming roller, it becomes deformed by the great heat to which it is there subjected.

According to the invention, the main portion of the strip passes from the forming roller to the next adjacent supporting means without support and over this gap it becomes substantially cooler, and can then be supported on a roller or on a stationary bed without difficulty. Narrow side members are then provided to support the edge portions in this gap so that they do not sag downwards and become stretched. The surface of these members is shaped to the curve taken by the main portion of the strip, so that they do not alter the normal course taken by the strip in passing over the gap.

In the accompanying drawing:

Figure 1 is a vertical cross-section of the device, showing a strip rolling apparatus partly broken away;

Figure 2 is a plan view of Figure 1 on a much reduced scale, omitting the upper roller, and

Figure 3 is a view similar to that of Figure 1

showing an alternative form of strip rolling apparatus.

Referring to Figures 1 and 2, the lower and upper rollers 1 and 2 respectively roll the molten glass 3 into a continuous strip 4, which is shown in dotted lines in Figure 2. After leaving the lower roller 1, at the point 5, the strip comes into contact with a stationary bed 6, at the point 7, and thereafter rests on the bed. The strip 4 in apparatus heretofore used, passes from the point 5 to the point 7 without support and it has been found, as mentioned above, that in this gap the edge portions of the strip sag downwards.

Side members 8 are supported on extensions 9 of the bed 6 and retained in place by projections 10 and engaging grooves 11 in the extensions. The side members 8 substantially bridge the gap between the lines of support at 5 and 7, and their outer surfaces 12 are curved to the curve which the strip takes in passing from one line of support to the other. The side members 8 then prevent downward sagging of the edges of the strip without altering the course of the strip in passing from the roller 1 to the bed 6.

Figure 3 shows the device applied to a rolling apparatus with roller bed of rollers 13, instead of a stationary bed, the upper roller 2 being omitted. The rollers are carried on side frames 14, and the side members 8 are bolted to extensions 15 of these frames.

The form of mounting of the side members 8 shown in Figures 1 and 2 permits the members being adjusted laterally in position, to suit different widths of strip.

A convenient width for each support has been found to be about two and a half inches, and it is preferable that the edge of the strip should overhang the support, as shown at 16, Figure 2, by a distance so small that the overhanging part does not sag. An overhang of $\frac{3}{8}$ inch has been found satisfactory for strip 10 mm. in thickness.

The supports may be made of various materials. Graphite has been found satisfactory, but is subject to wear. Cast iron or steel may be used if cooling means be provided. A metal of better heat conductivity, such as copper or brass may be used without special cooling means. The supports are chamfered on their inner edges 17 to prevent formation of a ridge on the strip.

By means of the invention, the advantage is retained of keeping the strip substantially free of any supporting means over an interval immediately following its formation, without any disadvantage due to sagging of the edges.

Having described my invention, I declare that what I claim and desire to secure by Letters Patent is:

1. The combination with a pair of forming rollers for rolling a continuous strip of glass, and a horizontal support for horizontally receiving the rolled strip thereon from the forming rollers and separated from said forming rollers by a gap over which the central body portion of the strip is unsupported, said horizontal support being also located beneath the point where the strip leaves the forming rollers so that the unsupported central body portion of said strip follows a curved path from the said forming rollers to the said horizontal support, of side members substantially bridging the gap located so as to support the edge portions only of the strip, the supporting surface of said side members being curved to correspond to the curve taken by the unsupported central body portion of the said strip in passing over said gap.

2. The combination with a pair of forming

rollers for rolling a continuous strip of glass, a horizontal support for horizontally receiving the rolled strip thereon from the forming rollers and separated from said forming rollers by a gap over which the central body portion of the strip is unsupported, said horizontal support being also located beneath the point where the strip leaves the forming rollers so that the unsupported central body portion of said strip follows a curved path from the said forming rollers to the said horizontal support, of side members substantially bridging the gap located so as to support the edge portions only of the strip, the supporting surface of said side members being curved to correspond to the curve taken by the unsupported central body portion of the said strip in passing over said gap, and means for adjustably mounting said side members for movement toward and away from one another so that the strip will overhang the said side members without sagging of the overhanging portions.

ERNEST BRISTOW LE MARE.
